US0D1023619S

(12) **United States Design Patent** (10) Patent No.: **US D1,023,619 S**
(45) Date of Patent: ** *Apr. 23, 2024

- (54) **CORNER DEVICE FOR A FLOOR COVERING**
- (71) Applicant: **Just Fur Love, LLC**, Boston, MA (US)
- (72) Inventor: **Allan Wendling**, New Lothrop, MI (US)
- (73) Assignee: **Just Fur Love LLC**, Boston, MA (US)
- (*) Notice: This patent is subject to a terminal disclaimer.
- (**) Term: **15 Years**
- (21) Appl. No.: **29/838,003**
- (22) Filed: **May 10, 2022**

CLAIM

The ornamental design for a corner device for a floor covering, as shown and described.

DESCRIPTION

FIG. 1 is an environmental perspective view of a corner device for a floor covering, shown mounted to an environmental floor covering;

FIG. 2 is a bottom plan view thereof;

FIG. 3 is a top plan view thereof;

FIG. 4 is a front view thereof;

FIG. 5 is a side view thereof;

FIG. 6 is a bottom plan view thereof, shown affixed to an environmental disk; and,

FIG. 7 is a top plan view thereof, shown affixed to an environmental disk.

The broken lines in the drawings depict environment of the corner device that forms no part of the claim.
